(57) CLAIM

The ornamental design for a toy building block, as shown and described.

DESCRIPTION

FIG. 1 is a front, right and top perspective view of a toy building block, showing my new design;
 FIG. 2 is a rear, left and bottom perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top plan view thereof; and,
 FIG. 8 is a bottom plan view thereof.

The broken lines shown in the drawings illustrate portions of the toy building block that form no part of the claimed design.
